UNITED STATES PATENT OFFICE.

CHARLES A. BENNETT, OF TAUNTON, MASSACHUSETTS, ASSIGNOR TO
REED & BARTON CORPORATION, A CORPORATION OF MASSACHU-
SETTS.

DESIGN FOR A SPOON OR FORK.

No. 37,709.

Specification for Design.

Patented Dec. 5, 1905.

Application filed October 19, 1905. Serial No. 283,553. Term of patent 14 years.

To all whom it may concern:

Be it known that I, CHARLES A. BENNETT, a citizen of the United States, residing at Taunton, in the State of Massachusetts, have invented a new, original, and ornamental Design for Spoons or Forks, of which the following is a specification, reference being had to the accompanying drawings, forming a part thereof.

Figure 1 of the drawings shows in plan the reverse side of a spoon or fork showing my

new design, and Fig. 2 is a plan view of the front or principal side of the spoon or fork.

I claim—

The ornamental design for spoon or fork, as shown.

CHARLES A. BENNETT.

In presence of—

GEORGE E. CHAMBERS,
HERBERT O. WOOLLEY.
